UNITED STATES PATENT OFFICE.

CHARLES E. BROOKS, OF ST. LOUIS, MISSOURI, ASSIGNOR TO B. ROTH TOOL COMPANY, OF ST. LOUIS, MISSOURI, A CORPORATION OF MISSOURI.

WINDING MECHANISM FOR EMBOSSED AND PRINTING PRESSES.

No. 926,715.

Specification of Letters Patent.

Patented June 29, 1909.

Original application filed March 31, 1908, Serial No. 424,308. Divided and this application filed June 29, 1908. Serial No. 440,798.

To all whom it may concern:

Be it known that I, CHARLES E. BROOKS, a citizen of the United States, and a resident of the city of St. Louis and State of Missouri, have invented a new and useful Improvement 5 in Winding Mechanism for Embossing and Printing Presses, of which the following is a specification.

The subject-matter of the present invention is divided out of an application for Letters Patent for improvements in embossing and printing presses, Serial No. 424,308, filed by me on March 31, 1908.

The present invention relates to the mechanism for winding waste paper and has for its principal objects to insure the taking up of the slack of the paper, to engage the winding drum and the actuating mechanism by a connection that will automatically yield 20 when the paper is stretched taut, to provide for the collapsing of the winding drum, and to secure other advantages hereinafter appearing.

It consists in the construction and arrangement of parts hereinafter described and claimed.

In the accompanying drawing, which forms part of this specification and wherein like symbols refer to like parts wherever they 30 occur, Figure 1 is a vertical sectional view of a winding mechanism embodying my invention; Fig. 2 is a detail view of the gear and its clutch element; Fig. 3 is a cross section of the winding drum on the line 3—3 of Fig. 35 1; Figs. 4 and 5 are cross sectional views taken on the same plane but looking in opposite directions, as indicated by the arrows in Fig. 1.

My winding mechanism is supported upon 40 any suitable device. In the accompanying drawing, it is illustrated on a bifurcated bracket 1 provided therefor on the frame of an embossing and printing press, and its relation to the other parts of such press are 45 more fully shown and described in my co-pending application No. 424,308, above mentioned.

The shaft or core 2 of my winding drum is journaled in horizontal hubs or bearings 50 provided therefor in the arms of the bracket. Rotatably journaled on this shaft or core between the arms of the bracket is a gear or pinion 3. Meshing with this pinion is a rack 4 which is adapted to be reciprocated by any

suitable mechanism, as for instance, the 55 mechanism illustrated in said application No. 424,308. One end of the pinion bears against an arm on the bracket and the other end is widened into an annular flange 5 upon whose face are mounted a series of gravity 60 pawls 6 and limiting stops 7 therefor. Loosely journaled on said shaft or core of the winding roll in the plane of said gravity pawls is a ring 8 whose periphery is toothed to form a ratchet wheel adapted to coöperate 65 with said gravity pawls. A similar toothed ring or ratchet wheel 9 is keyed to the core or shaft of the winding drum alongside of said first mentioned ratchet wheel. These two ratchet wheels constitute members of a 70 friction clutch. Above and in the plane of said fixed ratchet wheel are a plurality of gravity pawls 10 which are mounted on a plate 11 which is secured by pins or otherwise to the bracket 1 which supports the 75 winding drum.

The tubular core or shaft 2 of the winding drum has peripheral slots 12 through which projects a plate 13 which bears against the side of the first mentioned ratchet wheel or 80 clutch member 8 for the purpose of pressing it into frictional engagement with the fixed ratchet wheel. This plate or cross piece has a hole therein through which extends the reduced end of a rod 14 whose outer end rests 85 in the bore of a hollow nut 15 which is threaded to work in the threaded end of the hollow core of the winding roll. In the bottom portion of the bore or pocket of said nut is a spring 16 which presses against the end 90 of said rod. The projecting end of the nut is provided with a knurled head or handle 17 whereby it can be conveniently manipulated. By turning the nut, the pressure of the spring upon the rod is varied, 95 and thereby the friction between the clutch members 8, 9 is varied.

On the core of the winding drum are mounted a plurality of cylindrical segments 18, which are connected to the core by 100 means of parallel links 19. The outward movement of the links is limited by a collar 20 provided on the core for the purpose. The segments are supported in their extended position by means of a flanged sleeve 105 21 whose inner portion is adapted to fit on the core of the winding roll and whose projecting end is formed into a handle 22 for

convenient manipulation. Obviously, the withdrawal of this flanged sleeve or plug permits the segments to be collapsed and the waste paper to be withdrawn from the 5 roller drum.

The operation of the winding mechanism is as follows: The reciprocating movement of the rack bar 4 causes a forward and backward movement of the pinion 3 and of the 10 pawls mounted on the flange thereof. The forward movement of these pawls causes a forward movement of the rotatable ratchet wheel 8 which constitutes the movable member of the friction clutch. On account of 15 the frictional engagement of the clutch members, the rotation of the first member tends to rotate the second member of the clutch and consequently the core or shaft upon which it is fixed. The parts are so adjusted, however, that when the slack of the 20 waste paper is taken up, the actuating member of the clutch continues its movement without transmitting movement to the rear.

slots in its periphery, a ratchet wheel fixed on 85
said core, a stationary pawl in operative re-
lation to said ratchet wheel, a second ratchet
wheel loose on said core and having pawls ar-
ranged to engage such last mentioned ratchet
wheel, actuating mechanism operatively con-
nected to said second ratchet wheel, a rod in 90
said core having members projecting through
the slots therein and arranged to bear said
last-mentioned ratchet wheel against said
first mentioned ratchet wheel, and means for
varying the pressure of said rod.

6. A winding mechanism comprising a 95
winding drum having a hollow core having
slots in its periphery, a ratchet wheel fixed on
said core, a stationary pawl in operative re-
lation to said ratchet wheel, a second ratchet 100
wheel loose on said core, a pinion loose on
said core and having pawls arranged to en-
gage said last-mentioned ratchet wheel, a
rack meshing with said pinion, a rod in said
core having members projecting through the 105
slots therein and arranged to bear said last-
mentioned ratchet wheel against said first-
mentioned ratchet wheel, and a nut in the
end of said core having a spring arranged to
bear against the end of said rod and thereby 110
vary the pressure of one ratchet wheel
against the other.

Signed at St. Louis, Missouri, this 27th day
of June, 1908.

CHARLES E. BROOKS.

said core adapted to fit inside of said seg- 60
ments when the links bear against said
sleeve.

3. A winding drum comprising a core, a 65
pinion sleeved thereon, pawls mounted to
move with said pinion, a ratchet wheel swiv-
eled on said core in operative relation to said
pawls, a second ratchet wheel fixed to said
core, stationary pawls in operative relation
to said last mentioned ratchet wheel, and
means for frictionally engaging said ratchet 70
wheels with each other.

4. A winding mechanism comprising a 75
collapsible winding drum having a core, and a
friction clutch member fixed to said core, a
second friction clutch member loosely mount-
ed on said core in operative relation to said
first mentioned clutch member, actuating
mechanism operatively connected to said
second friction clutch member, and means
for preventing backward movement of the 80
winding drum.

5. A winding mechanism comprising a 85
winding drum having a hollow core having
25 provided for the driven member of
are located to operate serially, tha
instead of being spaced apart som
of the distance between adjacei
teeth, they are so positioned that
30 them are in operative engageme
same time, and, consequently, on
is in position to prevent the least
of the roll.

While I have described my dev-
35 plied to an embossing and printing
the purpose of winding waste wip
it is obvious that the invention is
application for winding sheets of
other materials that are fed inter
40 So, too, it is obvious that the n
hereinbefore described admits of
able variation without departing
invention, and I do not wish to be
to such specific mechanism.

45 What I claim is:

1. A winding drum comprising
plurality of spaced segments, par-
connecting said core and said segn
a plug mounted to move endwise of
50 said core being adapted to constit
ternal support for the ends of said
but being independent of and wit
from said segments to facilitate th
ing thereof.

55 2. A winding drum comprising
plurality of segments, parallel link
ing said core and said segments, a
said core for limiting the upward i
of said links, and a plug slidably m
